CHARCOAL RETORT

John Riley Wilkins, P.O. Box 307, Steelville, Mo.

Filed Sept. 28, 1956, Ser. No. 612,737.

2 Claims. (Cl. 202—98)

This invention relates to the carbonization of wood and more particularly to improved apparatus and method of making charcoal. One of the problems heretofore present in the carbonization of wood is that a considerable amount of the heat required to carbonize the wood is lost or otherwise dissipated outside the retort so that the heat is not efficiently utilized to do the work of making charcoal.

Accordingly, it is an object of the present invention to provide a charcoal retort having improved means for firing the wood or other material which is to be carbonized, which means is highly efficient and results in a minimum of heat loss so that a maximum amount of the heat generated is utilized in the carbonizing of the wood.

Another problem in producing charcoal resides in the cooling of the carbonized wood after the same has been heated sufficiently to drive off the distillation products. Unless the temperature of the charcoal is reduced below that capable of firing the same upon contact with oxygen, ignition will occur and, consequently, reduction in the quality of the charcoal results.

It is, therefore, another object of the invention to provide a retort of the type described having improved means for cooling the carbonized material under accurately controlled conditions so as to eliminate the possibility of ignition by maintaining the carbonized material out of contact with oxygen-containing gas until the carbonized material has been cooled to a low enough temperature to preclude ignition at atmospheric conditions.

A still further object of the present invention is the provision of a charcoal retort of the type described which is substantially continuous in operation, which insures an accurate temperature control of the charcoal during carbonization and which insures the cooling of the charcoal with a minimum danger of ignition.

A still further object of the present invention is the provision of a charcoal retort of the type described having improved means for handling the charges as they move through the retort chambers.

Still another object of the present invention is the provision of a novel method of making charcoal which embodies the steps of continuously introducing charges of wood or other material to be carbonized into an entrance chamber within a retort, progressively moving the charges through a heating chamber in which the charges are first preheated, then carbonized and finally precooled and then discharging the charges into a receiving chamber where they are finally cooled while substantially preventing any contact therewith of an oxygen-containing gas.

A further object of the present invention is the provision of a retort of the type described having improved means for introducing successive charges into the furnace compartment of the same.

A still further object of the invention is the provision of a retort of the type described having an improved heating chamber in which the charges are first preheated, then carbonized and finally cooled before being discharged.

2

Still another object of the invention is the provision of a retort of the type described having improved means for recovering the combustible gases driven off from the wood or other material during carbonization thereof and utilizing the combustible gases to provide heat for further carbonization.

Still another object of the invention is the provision of a retort of the type described having improved means for discharging successive charges from the heating chamber after carbonization and some cooling has been completed.

These and other objects will become more apparent during the course of the following detailed description and appended claims.

The invention may best be understood with reference to the accompanying drawings wherein an illustrative embodiment is shown.

In the drawings:

Figure 1 is a somewhat schematic side elevational view of a retort embodying the principles of the present invention;

Figure 2 is an enlarged end view of the retort with parts broken away for the purpose of clearer illustration;

Figure 3 is a vertical sectional view of the entrance chamber of the retort illustrating the manner in which successive charges are moved from the entrance chamber into the heating chamber of the retort;

Figure 4 is a side elevational view of the discharge end of the retort with parts broken away to illustrate the manner in which successive charges are removed from the firing chamber and discharged into the cooling chamber; and

Figure 5 is a cross-sectional view taken along line 5—5 of Figure 4.

Referring now more particularly to the drawings, there is shown in Figure 1 a schematic view of a retort, generally indicated at 10, embodying the principles of the present invention. The retort is preferably continuous in nature and disposed in a straight line so that successive charges of wood or other material to be carbonized may be introduced into the front end and discharged after carbonization has been completed from the rear end thereof. Of course, while it is preferred to construct the retort in a straight relationship, it will be apparent that a circuitous path may be employed, if desired. In general, the retort is divided into four separate compartments or chambers. Preferably, the first three compartments are in general longitudinal alignment with each other while the latter two may be vertically stacked, as will hereinafter be more fully described.

The forward end of the retort defines an entrance compartment or chamber 12 which is arranged to receive successive bins or hampers 14 charged with suitably formed wood or other material to be converted into charcoal. Figure 3 illustrates generally the construction of the bins or hampers which are preferably handled when outside the retort by wheeled carts or dollies 16. Disposed within the entrance chamber 12 is a means, generally indicated at 18, for receiving the hampers and for moving the same into a central firing or heating compartment or chamber

20 of the retort. The entrance chamber 12 is closed at its forward end by doors 22 and a vertically movable door 24 is disposed at its other end between the entrance chamber 12 and firing chamber 20. The means 18 is arranged to move successive charged hampers from the entrance chamber wherein they are supported by the dollies 16 through the door 24 and into the heating or firing chamber 20. Inside the firing chamber there is provided suitable heating means, generally indicated at 26, which is arranged so that successive charges during their travel through the firing chamber are first preheated, then carbonized and finally precooled to a substantial extent.

After the precooling of successive charges has been ac-

complished, the latter are moved out of the firing chamber and into a discharge compartment or chamber, generally indicated at 28. A means is provided within the discharge chamber 28 for opening and closing off the firing chamber with respect to the discharge chamber, for receiving the precooled carbonized wood-containing hampers from the firing chamber and moving the same into the discharging chamber, and for discharging the contents of the hampers into a receiving and cooling chamber or compartment, generally indicated at 32. The opening and closing means is also operable to discharge the empty hampers from the discharge chamber at the rear end of the retort.

In general, the operation of the retort is carried on substantially continuously so that when a charged hamper 14 is moved from the entrance chamber 12 into the firing chamber 20 by the operation of the means 18, a hamper containing carbonized and precooled material will be simultaneously moved out of the rear end of the firing chamber 20 and into the discharge chamber 28. The means 30 in the discharging chamber then dumps the charge from the hamper and discharges the empty hamper at the rear end of the retort.

The retort is preferably arranged so that the forward end is at an elevation slightly higher than the rearward end. That is, the retort is provided with a gradual slope of the order of one degree which facilitates the movement of the hampers therethrough. Of course, the operation of the retort can be carried out on any time cycle, but of primary significance is the fact that the entire operation is automatic so as to reduce to a minimum the requirements for attendants. The hampers which have been passed through the firing chamber are subsequently handled in a substantially oxygen-free chamber by means capable of dumping the carbonized and precooled contents thereof into a cooling chamber which likewise is maintained substantially free of oxygen. This discharging operation could not be accomplished manually since the temperatures present would prevent an attendant from gaining access thereto. Hence, the present arrangement insures that the carbonized material will be cooled to a sufficiently low temperature, without ignition, so that when the same is finally brought into contact with oxygen-containing gas, ignition is no longer possible.

Referring now more particularly to Figure 3, the construction of the entrance chamber 12 of the retort is shown in detail as including vertical side walls 34 connected at their upper ends by an upper wall 36. The floor of the chamber is preferably provided with tracks 38 for receiving and guiding the dollies 16. The dollies 16 may be of any suitable construction and, as shown in Figure 3, include a skeletonized frame 40 mounted on wheels 42. Suitably mounted on the upper surface of the frame 40 is a plurality of longitudinally spaced rollers 44 having outer flanges 46 thereon disposed to receive and guide the lower surface of the hampers 14.

The hampers 14 may also be of any suitable construction and, as shown, include a skeletonized box-like frame 48 having upper transverse end members 50 extending across the forward and rearward extremities thereof. Extending upwardly from the upper end of the skeletonized frame 48 at a position spaced inwardly from each end thereof is a pair of upright rigid members 52 carrying rollers 54 on the upper ends thereof.

The means 18 comprises a fluid pressure-operated ram unit 56 suitably mounted on the exterior of the chamber 12, as by bracket 57, in a position above the forward door 22 thereof. The ram unit 56 includes a plunger 58 which extends through the forward wall of the chamber 12 above the door 22 and into the chamber. Pivottally mounted on the rearward end of the plunger 58 is a hamper-engaging arm or member 60. A spring 62 is connected between the element 60 and the plunger so as to resiliently urge the latter against a stop element 64 rigidly

secured to the plunger 58. In this manner, a fully charged hamper moved into the entrance chamber 12 through the doors 22 will engage the element 60 and move the same rearwardly until the hamper reaches its fully extended position within the charging chamber. At this point, the trailing transverse member 50 of the hamper will have passed beyond the element 60 and the spring 62 will act to move the latter into a position behind the transverse member 50. This position is illustrated in Figure 3 and it will be noted that upon actuation of the fluid pressure-operated ram unit 56, as by suitable controls, not shown, the hamper 14 may be moved from the entrance chamber 12 into the heating or firing chamber 20 when the door 24 is open.

The door 24 is mounted for vertical sliding movement in an apertured partition 66 separating the chambers 12 and 20. Mounted on each side of the door 24 is a vertically extending rack 68. Each rack is engaged by a pinion 70 mounted on a common shaft 72 rotatably supported by any suitable means above the upper wall of the entrance chamber 12. The pinions 70 may be rotated by any suitable means, such as a reversible motor 74, connected to drive the shaft 72 as by a pair of sprockets 76 and a chain 78 trained thereabout. It will be understood that by actuating the motor 74 selectively in either direction, the door 24 may be selectively moved into an upper open position or a lower closed position.

The heating or firing chamber 20 preferably comprises side walls 80, each of which includes an exterior plate 82 of metal or the like and an interior wall 84 of brick or other refractory material and an intermediate layer 86 of a suitable insulating material. An upper wall 88 extends between the upper ends of the side walls 80 and includes an exterior plate 90 and interior transversely extending I-beams 92 or the like mounted on the upper ends of the interior walls 84. A layer of insulation 94 is mounted between the beams 92 and the exterior plate 90. Extending downwardly from the I-beams 92 is a plurality of hangers 96 which support a longitudinal housing 98 extending throughout the entire firing compartment 20. The housing 98 is rectangular in cross section and has a pair of transversely spaced tracks 100 mounted on the interior surface of the upper wall thereof. The tracks 100 may be of any suitable construction and (as shown, are in the form of conventional I-beams which provide channels within which the rollers 54 of the hampers 14 may ride. The tracks 100 thus serve to support the hampers in the firing chamber for movement through the housing 98 thereof.

As best shown in Figures 1 and 2, the heating means 26 preferably comprises a plurality of gas burners 102. These burners are disposed in the lower portion of the firing chamber below the housing 98 therein, which lower portion terminates intermediate the ends of the chamber 20, as shown in Figure 1. The terminal end of the lower portion of the chamber is open to the atmosphere, as at 104, for the introduction of air sufficient to support combustion of the burners. The forward end of the retort adjacent the entrance door 22 includes a lateral passageway 106 which leads to a stack 108 through which the combustion air in the firing chamber may discharge.

Of course, the placement of the burners with respect to the firing compartment will vary in accordance with the capacity of the retort. As shown, the first burner is disposed approximately midway between the ends of the chamber. There are two additional burners provided which are spaced toward the discharge end of the chamber and disposed within the area defined by the first burner and the opening 104 in the lower portion of the compartment. Of course, the heat generated by the burners will be most intense in the area immediately above the burners and since the flow of heated air is toward the forward end of the firing chamber, the rear end of the chamber will have the lowest temperature, with the temperature of the forward end gradually diminishing to

ward the stack. In this manner, the fresh charges entering the firing chamber through the door 24 will be preheated during their movement through the housing 98 for approximately one-half of their travel. This first area constitutes a preheating area where the sap or moisture in the wood or material being treated is driven off. Next, the charges enter a carbonizing area which is immediately above the burners where the products of distillation are driven off. Since the pressure created by the heat within the housing 98 is greater than atmospheric pressure, the products of distillation can be conveniently directed to the burners 102, as by pipes or conduits 110. In this manner, the combustible gases driven off in the carbonizing process are utilized to fire the burners, thus greatly increasing the efficiency of the retort. After the carbonizing area immediately above the burners 102 has been passed, the carbonized charges move toward the rear end of the firing chamber which constitutes a precooling area thereof. During this portion of travel the temperature of the charges is substantially reduced.

The discharging chamber 28 comprises a substantially semi-cylindrical vertical wall 112 of any suitable construction extending from opposite sides of the rear end of the firing chamber and having an upper wall 114 covering the same. Extending along the portion of the cylindrical wall 112 adjacent the end of the firing chamber 20 are upper and lower closure guide elements 116 within which an arcuate closure member 118 is slidably mounted. The closure member 118 includes an opening 120 which is arranged to be moved between a position adjacent the rear end of the firing compartment to permit discharge of the hampers therefrom and a position adjacent an opening 122 in the wall 112 which enables the empty hampers to be discharged from the chamber 28.

As best shown in Figure 4, the closure member 118 includes rigid arms 124 extending radially therefrom to a vertical shaft 126 pivotally supported at its lower end on a bearing block 128 or the like suitably mounted on the floor of the discharge chamber. At the upper end of the shaft 126, the upper wall 112 is provided with a circular opening, as indicated at 130, and a ring-shaped plate 132 is secured to the upper wall 112 adjacent thereto. The plate 132 is preferably provided with gaskets 134 of asbestos material or the like secured to both sides thereof. Rigidly mounted on the upper end portion of the shaft 126 is a pair of circular plates 136 which engage the gaskets 134 respectively on both sides of the ring plate 132. A series of circumferentially spaced rollers 138 are mounted between the plates 136 in a position to engage the inner periphery of the ring plate 132. In this manner, the upper end of the shaft is mounted for pivotal movement and a substantially airtight seal impervious to heat is formed at the point where the shaft extends out of the discharge chamber.

The shaft 126 and hence the closure member 118 is selectively moved in either direction by any suitable means, such as a reversible electric motor 140 secured to the exterior of the upper wall as by bracket 142. The drive shaft of the motor 140 is provided with a pinion 144 arranged to drive a large spur gear 146 or the like rigidly mounted on the upper extremity of the shaft 126.

The central portion of the shaft 126 is formed with a horizontal aperture 148 and a horizontal sleeve 150 is rigidly secured, as by bracing 152, to the shaft 126 in alignment with the aperture 148 and extends toward the closure member 118. A screw conveyor 154 has its rearward end portion journaled within the sleeve 150 and shaft aperture 148 and its forward end extending to a point adjacent the closure member opening 120. The screw conveyor 154 is thus mounted for pivotal movement with the shaft 126 and is rotated about its own axis by any suitable means, such as a reversible electric motor 156 fixedly mounted on the gear 146. The drive shaft of the motor 156 is provided with a pinion 158 which meshes with a cooperating gear 160 fixed to the

upper end of a vertical conveyor drive shaft 162. The shaft 162 extends downwardly through suitable gasketed apertures formed in the gear 146 and plates 136 to a point adjacent the rear extremity of the screw conveyor 154.

5 The lower end portion of the conveyor drive shaft 162 is journaled within suitable bearings 164 secured to the shaft 126 and its lower extremity has a bevel gear 166 fixed thereto which meshes with a cooperating bevel gear 168 fixed to the rear extremity of the screw conveyor.

10 Again, it will be understood that by selectively operating the motor 156 the screw conveyor 154 may be selectively rotated in either direction. This conveyor is adapted to receive the leading transverse member 50 of each successive hamper and, through its own rotation, to move the same into the discharging chamber in conjunction with its movement out of the firing chamber as a result of a charged hamper being introduced into the forward end of the chamber. It will be noted that the 15 position of the supporting rollers of each hamper is such that the trailing end of the same will leave the tracks 100 within the housing before the trailing transverse member 50 reaches a position sufficient to engage the screw conveyor 154. Consequently, as the trailing rollers leave the tracks, the trailing end of the hamper will swing downwardly with the connection of the leading transverse member with the conveyor acting as a pivot. In this manner, the fired contents of each hamper are dumped into a funnel-shaped bin 170 suitably mounted 20 below the discharging chamber at its forward end and leading to the receiving and cooling chamber 32.

25 A rotary valve assembly, generally indicated at 172, is disposed below the bin 170 so as to control the entrance of the heated charcoal into the receiving and cooling chamber 32. As best shown in Figure 4, the assembly 172 comprises a substantially cylindrical housing 174 having an upper opening 176 communicating with the lower end of the bin 170 and a lower discharge opening 178 communicating with the chamber 32. Journaled within the housing is a rotatable member 180 including a pair of spaced radial walls interconnected by a peripheral wall so as to define a wedge-shaped pocket 182. The member 180 is rotated by any suitable means, such as a motor 184 connected with the shaft thereof, 30 as by a belt 186 and pulleys 188 and 190.

35 The member 180 is preferably rotated continuously so that it will make a complete revolution each time a hamper is dumped. It will be noted that the construction of the rotary member 180 is such that when the 40 pocket 182 is in communication with the upper housing opening 176, the peripheral wall closes the discharge opening 178 and conversely, when the pocket is in communication with the lower opening, the upper opening is closed. The pocket 182 receives a full load of dumped 45 material through the upper opening and during the rotation of the member 180, the load is passed through the lower opening and into chamber 32 when the pocket 182 moves into communication therewith.

50 The receiving and cooling chamber may be of any suitable construction and as schematically illustrated in Figure 1, the floor of the chamber is inclined downwardly from the valve assembly 172 so that successive loads from the latter will move downwardly by gravity. The lower end of the chamber is provided with suitable means 55 (not shown) for permitting the cooled charcoal to be removed therefrom without substantial introduction of air. For example, a valve assembly similar to the assembly 172 may be utilized for this purpose. Where gravity feed is impractical, a drag chain may be provided in the chamber 32 for moving successive loads from the valve assembly 172 to the discharge end of the chamber 32.

55 The retort of the present invention is adapted to be continuously operated and the time interval in which successive charged hampers are introduced into the retort varies in accordance with the capacity desired. It will

be understood that the empty hampers are first loaded with suitable charges of material, such as wood or the like, which are to be made into charcoal. During the loading of the hampers 14, the dollies 16 are utilized to handle the same outside the retort so that they may be readily introduced therein through the entrance chamber 12. A freshly charged hamper 14 is moved into the entrance chamber 12 on a supporting dolly 16 by opening doors 22 and moving the dolly inwardly on tracks 38 until the leading end engages partition 66. During this movement, the hamper-engaging member 60 is pivoted out of the way and spring urged back into an operative position capable of engaging the trailing transverse member 50 of the hamper. Doors 22 are immediately closed after the entrance of the hamper. Before actuation of the ram unit 56, the door 24 must be opened and, hence, motor 74 is actuated for this purpose. It will be noted that the manner in which the hampers are moved through the housing 98 is by interengagement with each other and, hence the movement of a newly charged hamper into the forward end of the chamber will also result in the movement of a hamper containing carbonized and precooled charges out of the rear end of the firing compartment. Consequently, the closure member 118 of the discharging compartment must be moved from its normally closed intermediate position into a position in which the opening 120 is aligned with the rear end of the firing chamber. Consequently, the motor 140 of the means 30 is simultaneously actuated with the motor 74 so that both the forward and rearward ends of the firing compartment are open.

After door 24 is opened, the hydraulic ram unit 56 is actuated so as to move the plunger 58 thereof and, hence, the member 60 into engagement with the hamper. This movement of the fluid-operated ram unit 56 moves the newly charged hamper 14 into the firing compartment and the hamper containing a carbonized and precooled charge out of the rear end thereof. It will be noted that the leading rollers 54 of the hamper in the entrance chamber are positioned with respect to the leading end of the hamper so that they will enter the adjacent ends of the tracks 100 before the center of gravity of the hamper moves beyond the leading edge of the dolly 16. That is, the weight of the hamper 14 is supported by the dollies until the leading rollers 54 engage within the tracks. Further movement of the fluid-operated ram unit 56 will also engage the trailing rollers 54 within the ends of the tracks 100. In this regard, it will be noted that the position of the trailing rollers with respect to the trailing end of the hamper is such that they will enter the ends of the tracks before the trailing end of the hamper leaves the leading end of the dolly. That is, the dolly serves to support the trailing end of the hamper until the trailing rollers 54 enter the tracks 100.

At the same time that the ram unit 56 is actuated to move the newly charged hamper 14 into the firing chamber, the motor 156 controlling the screw conveyor 154 is also actuated so that when the leading rollers 54 leave the ends of the tracks 100 the leading transverse member 50 will fall on the conveyor 154 and be moved rearwardly by the rotation thereof. In this regard, it will be noted that the leading transverse member 50 is disposed ahead of the leading rollers 54 thus enabling the same to move into an overlying position while the hamper is supported in a horizontal position by the engagement of the rollers within the track. Conversely, the trailing rollers are disposed ahead of the trailing transverse member so that they will leave the ends of the tracks before the trailing transverse member will have moved into an overlying position with respect to the screw conveyor 154. In this manner, as was briefly noted above, the trailing end of the hamper is allowed to swing downwardly, with the engagement of the leading trans-

verse member 50 with the screw conveyor acting as a pivot, and dump the contents into the bin 170. It will be understood that the leading transverse member 50 may be formed with suitable central U-shaped portions (not shown) or the like which would center the hamper thereon and effectively prevent lateral tilting thereof.

When the newly charged hamper has been moved completely into the firing chamber, that is, at the end of the ram unit stroke, a suitable means, such as a switch or the like (not shown), is engaged which serves to reverse the operation of the ram unit and, hence, retract the same and at the same time reverse the operation of the motor 74 so as to effect closure of the door 24.

Simultaneous with this movement, the hamper in the discharge chamber moving on the screw conveyor 154 engages a suitable means, such as a switch or the like (not shown), when it reaches an inner limiting position on the screw conveyor. This switch serves to shut off the motor 156 or at least reverse its operation and also to actuate the motor 140 so as to pivot the shaft 126 in a counter-clockwise direction as viewed in Fig. 5. The initial portion of the movement of the shaft 126 will effect the closure of the rear end of the firing compartment by the closure member 118 and upon further movement thereof the opening 120 registers with the opening 122 to permit the hamper to be discharged therethrough. When the shaft has been rotated into its limiting position, as shown in dotted lines in Figure 5, another switch or the like, is actuated which de-energizes the motor 140 and again energizes the motor 156 in reverse direction so as to operate the screw conveyor 154 and, hence, move the hamper out through the opening 122. At the end of this movement another switch is actuated to move the shaft and closure member to its normally closed position intermediate its limiting positions.

From the above it can be seen that for each newly charged hamper which is moved into the forward end of the firing chamber, there is a hamper containing carbonized and precooled material leaving the rear end of the chamber. In this manner, the charges are moved substantially continuously through the charging chamber and are handled at each end thereof by means which can be made to operate fully automatic by the use of a suitable electrical circuit or the like, as is well known in the art. As was briefly noted above, the operation and position of the burners in relation to the flow of air sufficient to support combustion is such that the hampers disposed in the forward portion of the firing chamber are preheated so that the sap and other moisture, in the case of wood, will be driven off before the charges are moved into a position directly above the burners where the heat is most intense. The construction of the housing within the walls of the firing chamber is such as to most efficiently transfer the heat of the burners to the charges of the hampers. The walls of the chambers are highly insulated and a good circulation around the entire housing 98 is obtained. The walls of the housing are preferably good heat conductors, but are also imperforate so that the pressure within the housing will be maintained somewhat higher than in the lower portion of the chamber where the flow of combustion air occurs. With this arrangement a very rapid heat transfer is obtained and the gases discharging through the stack 108 do not carry off a substantial amount of heat which would be additionally useful in carbonizing the charges.

The arrangement also makes possible the recovery of combustible gases driven off from the charges during the carbonization thereof. As was noted above, the carbonizing of the charges occurs when the same are moved through the area of the housing disposed directly above the burners. Since the pressure within the housing is greater than the pressure existing in the lower portion of the chamber, the combustible products of distillation in the form of gases or the like may simply be directed to the burners through suitable conduits connected be-

tween the burners and the interior of the housing. Of course, with this arrangement a substantial saving in the amount of fuel utilized to heat the charges and carbonize the same is effected. After the hampers move past the area within the chamber directly above the burners, the temperature is reduced somewhat and the carbonized material is allowed to cool while within the firing chamber. This precooling of the carbonized charges before discharge from the firing chamber is significant in that the gas medium contained within the housing 98 is substantially free from oxygen and, hence, combustion of the carbonized material is precluded. When the hampers reach the rearward end of the firing chamber the temperature of the charges therein has been substantially reduced. However, if placed in contact with the atmosphere, combustion would result due to its temperature and the oxygen in the air. The discharge chamber 28 is maintained closed during most of the operation of the retort and when the rear end of the firing chamber is open and communicates therewith, it will be understood that, due to the heat in the firing chamber, its pressure will be above that within the discharge chamber. Consequently, any flow of gaseous medium between the chambers when they are in communication will be from the firing chamber into the discharge chamber. In this manner, during the normal operation of the retort the discharge chamber is also filled with a gaseous medium which is at most very low in oxygen content, if not entirely free thereof. At any rate, with the rear end of the firing chamber in communication with the discharge chamber the tendency is for the gaseous medium in the former to flow into the latter. Thus, as the hamper moves out of the firing chamber and into the discharge chamber substantially no oxygen will come in contact therewith. As was stated above, the action of the rotary valve assembly 172 is such as to prohibit free communication between the discharge chamber and the receiving and cooling chamber. Consequently, the carbonized material is cooled to a temperature below which combustion would be caused in the atmosphere, while at all times preventing contact of any gas which would contain sufficient oxygen to support combustion. This arrangement insures that a high-grade charcoal will be produced.

It thus will be seen that the objects of this invention have been fully and effectively accomplished. It will be realized, however, that the foregoing specific embodiment has been shown and described only for the purpose of illustrating the principles of this invention and is

subject to extensive change without departure from such principles. Therefore, this invention includes all modifications encompassed within the spirit and scope of the following claims.

- 5 I claim:
1. In a charcoal retort, the combination comprising: means defining a discharge chamber for the retort including an arcuate wall having a first opening therein for receiving successive hampers containing fired charges of material to be made into charcoal and a second opening for discharging empty hampers from the chamber; an arcuate closure plate for selectively closing said openings; an upstanding member pivotally mounted about the axis of said arcuate wall and closure plate, means connecting said closure plate for pivotal movement with said member; and means carried by said member for pivotal movement therewith between a first position in alignment with said first opening and a second position in alignment with said second opening for handling successive hampers within said chamber, said last-mentioned means being operable in said first position to engage successive hampers entering said first opening and dump the contents thereof and operable in said second position to discharge successive empty hampers through said second opening.
  2. The combination as defined in claim 1 wherein said last-mentioned means comprises a screw conveyor.
